UNITED STATES PATENT OFFICE.

IRVING C. WOODWARD, OF CHICAGO, ILLINOIS.

SELF-LOCKING SCREW-THREAD.

1,300,801.

Specification of Letters Patent. Patented Apr. 15, 1919.

Application filed July 12, 1918. Serial No. 244,590.

To all whom it may concern:

Be it known that I, IRVING C. WOODWARD, a citizen of the United States of America, and a resident of Chicago, county of Cook, 5 and State of Illinois, have invented certain new and useful Improvements in Self-Locking Screw-Threads, of which the following is a specification:

This invention relates to self-locking 10 screw threads of the character described in Patent No. 1,250,748, of December 18, 1917. The type of thread described in said patent is the standard V thread having a uniform cross sectional area, but with the apex of 15 the thread slightly offset from the center line of the thread. The purpose of so uniformly offsetting the apex of the thread was to cause it to resiliently or frictionally engage a coacting thread by said coacting 20 thread forcing the apex toward normal relationship with the body of the thread. The purposes of the present invention are the same as those of the prior invention, being to provide an improved form of thread 25 which is self-locking to secure a nut in any position on a bolt regardless of the pressure between the nut and the part which is to be retained in place on the bolt, and to provide locking threads which are uniform 30 in cross sectional area and are of uniform pitch, and which may be cut by the same operations which are employed to cut the well-known forms of non-locking threads.

The present invention differs from the 35 aforementioned prior invention in that instead of offsetting the apex of the thread, the thread is so cut that its base is slightly out of normal position. Thus, such a thread when coacting with a normal thread forces 40 the apex of the normal thread slightly to one side, and in this manner causes the threads to frictionally engage each other and form a substantially locked arrangement.

45 An illustrative embodiment of the invention is shown in the accompanying drawings, in which—

Figure 1 is a sectional view of the nut.

Fig. 2 is an enlarged cross sectional view 50 of the improved thread.

The advantages of the present construction over many other forms of self-locking threads are that the strength of a standard V thread is not affected by the improved 55 design, and may have the usual uniform pitch and requires but a single operation

in cutting and may be cut by a tap or die, which only in a minute degree differs from normal taps and dies.

In the construction shown, the interfitting or coacting threads on the nut or bolt are of practically equal cross sectional area as standard threads and are formed to provide a snug fit along their entire surface in the same manner as do the standard 60 forms of threads now commonly in use.

The sole difference of the present invention and the well-known standard threads is that one thread of a pair of coacting threads has its base slightly to one side 70 of a center line passing through the apex of the thread. A thread so formed when coacting with a normal thread serves to force slightly to one side the apex of the coacting thread and accordingly effect a 75 resilient and more or less locking engagement between the two threads.

In the drawing, a bolt 1 is shown provided with the well-known form of V thread 2, while the nut 3 has a thread 4 so cut as 80 to be practically equal in cross sectional area to the thread 2, but with its base so formed that its center 6 (Fig. 3) is slightly to one side of the center line 7 passing through the middle of the apex of the 85 thread. This view of the drawing for the sake of clearness exaggerates the offsetting of the base of the thread, the appearance of the actual thread being not perceptibly different from the appearance of a normal 90 V thread.

According to the above the threads 2 and 4 are uniform in pitch, height and width at the base and are also uniform in cross sectional area, the only difference being that 95 one thread has a base which is not in quite true relation to the apex of the thread.

The invention may be applied to threads having sharp, flat or rounded apices, but in all cases the thread is of substantially that 100 form generally approved and generally in use and not differing therefrom in extent of bearing area.

When the nut is applied to the bolt, the thread 4 of the nut causes the apex of the 105 thread 2 to be resiliently forced slightly to one side, and thus effect the desired frictional engagement between the threads.

Although but one specific embodiment of this invention has been herein shown and 110 described, it will be understood that numerous details of the construction shown may

be altered or omitted without departing from the spirit of this invention as defined by the following claims:

I claim:

5 1. A threaded member, the thread of which is of uniform pitch and has sides extending at equal angles from the apex of the thread, except that at the base or root of the thread the sides slope inwardly on 10 one side, and outwardly on the opposite side from the normal angle.

15 2. A pair of complementary threaded members, one having a standard thread of equilateral triangular cross-section, and the other having a thread of equal cross sectional area and of like triangular form,

except that at the base of the thread the sides slope inwardly on one side, and outwardly on the opposite side from the normal angle.

20 3. A pair of complementary threaded members, one having a standard thread of triangular cross-section, and the other having a thread of equal cross sectional area and of like triangular form, except that at 25 the base of the thread the sides slope inwardly on one side, and outwardly on the opposite side from the normal angle.

Signed at Chicago this 8th day of July, 1918.

IRVING C. WOODWARD.
